US00D459246S

(12) **United States Design Patent** (10) Patent No.: **US D459,246 S**
Power et al. (45) Date of Patent: ** Jun. 25, 2002

(54) **HAND-HELD METAL DETECTOR**

(75) Inventors: **John Michael Power; Gerald Lee Johnson**, both of Garland, TX (US)

(73) Assignee: **Garrett Electronics, Inc.**, Garland, TX (US)

(**) Term: **14 Years**

(21) Appl. No.: **29/150,625**

(22) Filed: **Nov. 26, 2001**

(51) LOC (7) Cl. **10-04**

(52) U.S. Cl. **D10/47**

(58) Field of Search D10/47; 324/328, 324/233, 329; 340/368
